(57) **CLAIM**

The ornamental design for a beauty control hub of facial massager as shown and described.

DESCRIPTION

1. Beauty control hub of facial massager

1.1 : Perspective

1.2 : Front

1.3 : Back

1.4 : Left

1.5 : Right

1.6 : Bottom

1.7 : Top

Fig. 1.1 is a top right front perspective view of a beauty control hub of facial massager showing my new design; fig. 1.2 is a front view thereof; fig. 1.3 is a rear view thereof; fig. 1.4 is a left view thereof; fig. 1.5 is a right view thereof; fig. 1.6 is a bottom view thereof; fig. 1.7 is a top view thereof; in the drawings, the broken lines show unclaimed subject matter only and form no part of the claimed design; fig. 1.1 best represents the essential feature of the design; the design is distinguished by shape.
